CARDING ENGINE

Hiroshi Ohnishi, Ashiya City, Japan

Application January 25, 1955, Serial No. 483,891

8 Claims. (Cl. 19—99)

The present invention relates to a carding engine for carding textile fibers, and more particularly to a carding engine for carding cotton fibers.

There are known carding engines for carding cotton fibers with one or several revolving flat card portions and carding engines for carding wool with one or several pairs of a worker and a stripper card also known as roller and clearer card portions.

Cotton carding engines as heretofore known do not produce entirely satisfactory carding results for certain kinds of cotton fibers. The workers and strippers of conventional wool carding engines, while being highly useful for loosening the fibers of wool especially of long-fiber material, have been found not to be suitable for use in the cotton industry, except possibly for a limited use in cotton coarse spinning.

The principal object of the present invention is to provide a novel and improved carding engine especially of carding of cotton fibers, which combines the advantage of carding by a revolving flat card portion with the advantages of carding by a worker and stripper card.

Another object of the invention is to provide a novel and improved mixed or combined carding engine which produces a sliver consisting of well loosened and parallel fibers and lending itself very well to drawing.

Still another object of the invention is to provide a novel and improved carding engine, the carding action of which prevents or at least greatly reduces the formation of neps and nits.

A further object of the invention is to provide a novel and improved carding engine, the carding action of which is such that substantially all the fiber material fed to the engine is delivered in carded condition to the doffer of the engine. This affords an important advantage over carding engines as heretofore known in which a substantial portion of the useful fiber material is accumulated in the flat carding portions and has to be removed therefrom as waste.

A still further object of the invention is to provide a novel and improved carding engine which conveniently permits the adaptation of the carding action to different types of fiber material by varying the speed of the revolutions of the flat card portions.

According to the invention, the aforementioned and other objects, features and advantages are attained by providing several revolving flat card portions and a roller card including a stripper and a worker between each two flat card portions so that the carding action to which the web of fibers is subjected changes from that of a flat portion to that of a worker and stripper card and back again to that of a flat card portion. As a result of this repeated change in the carding action the aforementioned advantages are attained.

In the single figure of the accompanying drawing, a preferred embodiment of the invention is shown by way of illustration and not by way of limitation.

Referring to the drawing, it is apparent that the exem-

2

plified carding engine according to the invention is arranged for rotation in counterclockwise direction as seen in the figure, that is, the fiber material to be carded is fed to the engine at the right side thereof and is removed therefrom at the left side.

Accordingly, the fiber material such as cotton is fitted in a suitable manner in a slotted standard 1 from where it is transferred to a taker-in or licker-in 2 which feeds the material to the main cylinder or swift 3. The cylinder coacts with a first or anterior revolving flat portion generally designated by 4, a second or posterior revolving or flat portion generally designated by 5 and a roller card generally designated by 6 and disposed between the two flat portions. Each of the two flat portions comprises an endless chain or belt 7, guided over rollers 8 and 9. Each of the chains or belts has the conventional stroking clothing 7' including a multitude of pins. Each of the flat portions is further provided with a spring loaded tensioning device 10 of conventional design to permit adjustment of the tension of the revolving chain or belt 7.

To permit removal of fibers accumulating on the flat portions a cleaning device 11 is provided for each flat card portion. Each of the cleaning devices comprises a rotary cylinder 12 from which radially extend pins or bristles 13 to comb fibers out of flat card portions. As may be noted, the cleaning devices 11 coact with the outside of the belt or chain 7. A further cleaning device 14 also provided with revolving bristles or needles 15 coacts with the inside of chain or belt 7 or flat card portion 5.

The roller card 6 comprises a worker 16 also called a roller and a stripper 17 also called a clearer roller. Stripper 17 is disposed adjacent to the posterior end of flat card portion 4 in coaction with this end and also with the worker and the cylinder. The worker in turn coacts with the anterior end of flat card portion 5 and the cylinder.

The fiber material after leaving flat card portion 5 is transferred to a doffer 18 from which it is removed in a conventional manner for further operations.

The taker-in 2, the cylinder 3 and the doffer 18 are driven from a motor 20 with which they are coupled by suitable transmission means such as belts 21, 22 and 23 and a pulley 24.

The operation of the carding engine as hereinbefore described is as follows:

The raw fiber material after leaving taker-in 2 is transferred to main cylinder 3 and first carded between flat card portion 4 and the cylinder in a well understood manner.

During this carding operation, part of the fiber material will be retained in the clothing of card portion 4. Such retained fiber material, which in conventional carding engines would be waste, is substantially recovered from the clothing of card portion 4 by the coaction of stripper 17 with card portion 4 at point a and returned to the cylinder at point b. As is apparent, card portion 4 and stripper 17 revolve in opposite directions. Furthermore, fiber material accumulating on worker 16 will be substantially recovered therefrom at point c and also deposited by the stripper at point b. As a result, practically the entire fiber material transferred by taker-in 2 to the cylinder will reach the second or posterior flat card portion 5. When the fiber material reaches this second flat card portion, it has already undergone a substantially stroking and straightening action so that the loss of fiber material in the second flat card portion is comparatively negligible.

Practical tests have shown that a carding engine according to the invention produces an excellent carding effect with a minimum of waste.

By varying the adjustment of the flat card portions, the same can be set for different speed depending upon the properties of the fiber material to be carded.

While the invention has been described in detail with respect to a certain preferred example and embodiment of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. A carding engine for carding textile fibers, comprising a rotatable main cylinder, feed means for feeding fiber material over said cylinder and through the engine, a pair of circumferentially spaced revolving flat card portions coacting with the cylinder to effect carding of fiber material fed thereto, and a roller card portion including a worker and a stripper card disposed between said two flat card portions in coaction with each other, the flat card portions and with the cylinder to effect carding of fiber material fed thereto.

2. A carding engine according to claim 1, wherein the said stripper card is disposed adjacent to the posterior end of the anterior flat card portion as seen in the direction of travel of the fiber material, in coaction with said end.

3. A carding engine for carding textile fibers, comprising a taker-in, a main cylinder following said taker-in, a first revolving flat card portion in coacting relationship with said cylinder, a roller card including a worker and a stripper card in coacting relationship with each other and said cylinder following said flat card portion, the stripper card being disposed between the flat card portion and the worker, a second revolving flat card portion in coacting relationship with the main cylinder following said worker, and a doffer following said second flat card portion.

4. A carding engine according to claim 3, and further comprising first cleaning means disposed at the rear end of the first flat card portion in coacting relationship therewith, and second cleaning means disposed at the rear end of the second flat card portion in coacting relationship therewith.

5. A carding engine according to claim 4, and additionally comprising third cleaning means coacting with

said second flat card portion, said second cleaning means being disposed for action upon the outside of said second flat card portion and said third cleaning means being disposed for action upon the inside of said second flat card portion.

5 6. A carding engine according to claim 3 and further comprising adjustable tensioning means coacting with said first flat card portion for adjusting the tension thereof, and adjustable tensioning means coacting with said second flat card portion for adjusting the tension thereof.

10 7. A carding engine for carding textile fibers comprising a revolving cylinder, feed means for feeding fiber material to be carded to and over said cylinder, an anterior revolving flat card portion disposed in coacting relationship with said cylinder, a revolving stripper following said flat card portion in the direction of travel of the fiber material of the cylinder, a revolving worker following the stripper, and a posterior revolving flat card portion following the worker and disposed in coacting relationship with the cylinder, said stripper coacting with the forward end of the posterior flat card portion for stripping fiber accumulations from said forward end and returning the accumulations to the cylinder, and said worker coacting with said stripper and the rear end of said anterior flat card portion for stripping fiber accumulations from the stripper and said rear end and returning the said accumulations also to the cylinder.

15 8. A carding engine according to claim 7 wherein said two flat card portions, said stripper and said worker all revolve in the same direction whereby the coacting circumferential surfaces thereof meet each other in opposite direction.
